UNITED STATES PATENT OFFICE.

GEORGE J. LEDERER, OF PROVIDENCE, RHODE ISLAND.

DESIGN FOR A WATCH-FACE PROTECTOR.

52,845.

Specification for Design.

Patented Jan. 7, 1919.

Application filed August 13, 1918. Serial No. 249,742. Term of patent 3½ years.

To all whom it may concern:

Be it known that I, GEORGE J. LEDERER, a citizen of the United States, residing at the city of Providence, county of Providence, State of Rhode Island, have invented a new, original, and ornamental Design for a Watch-Face Protector, of which the following is a specification, reference being had to the accompanying drawing, forming part thereof.

I claim:

The ornamental design for a watch face protector, as shown.

GEORGE J. LEDERER.
